C. PHELPS.
SUPPORTING TABLE LEAVES.

No. 10,285.

Patented Nov. 29, 1853.

UNITED STATES PATENT OFFICE.

CHARLES PHELPS, OF SALEM, MASSACHUSETTS.

SUPPORTING FALLING TABLE-LEAVES.

Specification of Letters Patent No. 10,285, dated November 29, 1853.

To all whom it may concern:

Be it known that I, CHARLES PHELPS, of Salem, in the county of Essex and State of Massachusetts, have invented a new Mode 5 of Supporting Table-Leaves in a Horizontal Position; and I do hereby declare that the following is a full and exact description.

I call it a self acting support for table leaves. It is composed of three pieces of 10 cast iron or any other suitable material, and a spring of steel or any other suitable material; the apparatus is represented in the drawings (hereto annexed) by the letters D, B, A, E.

15 D is a plate of iron screwed to the under side of the leaf when in a horizontal position to which the brace B is attached by a hinge joint. The brace B is a bar of iron about twelve inches in length, with a curve 20 at the upper end, forming the handle C in the plan; at the other end there is a projection represented by F on the upper side, and the spring on the under side represented by the letter E.

25 A is a plate of iron about five inches in length and about one inch wide, through which near the lower end there is an oblong hole about one and a quarter inches long and five eighths of an inch in width; 30 near the upper part of said hole there is a pin which crosses it marked G on the plan; this plate is screwed to rail of the table near the center thereof projecting below it from one to two inches; the pin G forms a rest 35 for the projection F when the leaf is up.

The action of the parts is as follows: When the leaf is down or in a perpendicular

position, the brace is in the position represented on the right of the plan passing through the hole in the plate A and under the table. On raising the leaf to a horizontal position the brace B is drawn through the hole in plate A till when near the end the spring E is pressed close to brace B by 40 the catch F passing under pin G. After 45 passing, the brace B rises carrying the catch F, above the pin G by the action of the spring on the lower part of the hole in A marked G''. The brace is released by drawing the handle C toward the edge of the 50 leaf, which draws the catch F below the pin G and allows the brace to pass through the hole in A.

I do not claim merely the application of a hinged brace for supporting the leaf of a 55 table, as that is a device well known for like purposes; nor do I claim the making it slide in a staple, or guiding aperture; neither do I claim the use of a spring for throwing it into its catch, merely as such; 60 but

What I claim is—

The application to the falling leaf of a 65 table, of a hinge supporting brace, in the form of a bent lever combined with a spring on the under side, for throwing it upward into its catch; whereby the table leaf can be conveniently released to let down by a pull at the short arm of the bent lever as described.

CHARLES PHELPS.
